UNITED STATES PATENT OFFICE.

CHARLES HABART, OF CLEVELAND, OHIO.

CUTTING IMPLEMENT.

Application filed November 9, 1921. Serial No. 513,891.

To all whom it may concern:

Be it known that I, CHARLES HABART, a citizen of the United States, residing at Cleveland, in the county of Cuyahoga and State of Ohio, have invented a certain new and useful Improvement in Cutting Implements, of which the following is a full, clear, and exact description.

The present invention relates to a cutting implement in which a pair of knives are mounted to cut in parallel relationship, together with means by which the distance between the knives may be definitely regulated.

The device is particularly intended for use as a candy cutter, same being used in connection with the cutting of soft candy, such as fudge; however, this forms no limitation upon its use for other purposes.

Reference should be had to the accompanying drawings forming a part of this specification, in which Fig. 1 is a top plan view; Fig. 2 is a side elevation; Fig. 3 is a partial top plan view showing a modified structure; Fig. 4 is a partial side elevation showing a modified construction.

Referring to the drawings, 1 indicates what may be described as a U-shaped frame member which is conveniently made out of metal having a flat central portion and upstanding sides. To this member 1 is adapted a handle which is indicated at 1^a, this handle being secured in any desired manner.

Co-operating with the frame member 1 is a U-shaped support 2, this support preferably comprising an end member 2^a and side members 2^b. Extending between the side members 2^b and spaced from each other are two spacer rods 3 and 4, these members being secured to the sides 2^b in any desired manner, but rigidly secured so as to definitely form a rigid structure.

The U-shaped member 2 is pivotally mounted upon the frame 1 and this is accomplished by means of short bolts such as indicated at 5 which extend through suitable openings formed in the side members 2^b of the member 2, and in the upstanding sides of the frame 1. Nuts 6 co-operate with the bolts 5 so that the member 2 may be adjusted with respect to the frame member 1.

Between the side members 2^b of the member 2 there are supports which are indicated at 7 and 8, these supports being provided with openings through which extend the

members 3 and 4. These supports 7 and 8 are, however, directly mounted upon short sleeves such as indicated at 9 and 10, which sleeves are slidably mounted on the members 3 and 4. The construction just described enables these supporting members 7 and 8 to be moved toward and from each other by a sliding movement on the members 3 and 4.

Extending transversely between the side members 2^b is a threaded member 11, the opposite ends of which are provided with a left hand and a right hand screw respectively. One end of the member 11 is mounted for turning movement in one of the side members 2^b while in the other end of this member it extends through an opposite side member 2^b and is provided with a member 12 that has a flat upstanding rib 13 which may be grasped by the fingers of a user so as to give turning movement to the screw 11. On the screw are two oppositely disposed interiorly threaded sleeves 14. These sleeves being fastened to the supporting members 7 and 8 so that as the sleeves are extended to move longitudinally with respect to the member 11 by the turning thereof, they will cause corresponding movement of the supporting members 7 and 8 toward or from each other.

At the outer ends of the supporting members 7 and 8 there is mounted a threaded stud 15 which upon the threaded end thereof has a nut 16. The sleeves 10 are notched out as indicated at 10^a and are adapted to receive the slotted end 17 of a cutting knife 18. This knife is also provided with a second slot indicated at 19 which is in the upper side of the knife. This slot is adapted to co-operate with one of the studs 15 and the knife is mounted by passing the slot 17 into co-operation with the notched portion of the member 10 and the slot 19 into co-operation with the stud 15, thereupon the nut 16 is tightened, thus securely holding the knife in position.

The construction by which the second knife is mounted and held is precisely the same as that which has been just described.

The knife is used by grasping the handle 2 and pressing the points of the knife into the object to be cut with the various parts which have been described in the position shown in Fig. 2. By virtue of the pivotal connection between the frame 1 and the U-shaped member 2, the angularity of the

handle with respect to the cutting knives may be adjusted to suit the desire of the user.

In the construction shown in Figs. 3 and 4, the parts which are there shown are precisely the same as in the above described construction, with the exception that in the form shown in Figs. 3 and 4, there is secured on the outside of each of the members 7 and 8 an additional part which adapts the device for use with thin lathed cutting knives.

Referring to Figs. 3 and 4, 20 indicates a member which is secured to the outer end of the member 7 by means of short bolts and nuts 23. This member is provided with a groove 21, which when the member 20 is secured against the member 7, forms in effect a slot, and this slot is diagonally arranged with respect to the major axis of the member 7. This slot is of sufficient width to receive a thin knife 22. In order to hold the knife from slipping after the knife blade has been inserted the nuts 23 will be tightened and so clamp the knife.

Having described my invention, I claim:—

1. A cutting implement comprising a frame having side members, parallel transversely extending bars between and mounted upon the said side members, a pair of knife supports at least one of said supports being mounted to slide upon the said transverse bars, and means carried by the said members of the frame and engaging one of the knife supports to adjust the same longitudinally of the supporting bars.

2. A cutting implement comprising a frame having side members, a pair of parallel transversely extending bars which at their ends are mounted in the side members of the frame, a pair of knife supports at least one of said knife supports being mounted upon the said cross bars so that the support may slide thereon, and a screw member journaled in a side member of the frame co-operating with a threaded portion of said knife support whereby it may be adjusted as to its position upon said bars.

50 3. A cutting implement comprising a frame having side members, a pair of par-

allel transversely extending bars which at their ends are mounted in the side members of the frame, a pair of knife supports each of which is mounted upon the said bars and adapted to slide thereon, and means carried by the side members of the frame and engaging the said knife supports to adjust the same with respect to each other.

4. A cutting implement comprising a frame having side members, a pair of parallel transversely extending bars which at their ends are mounted in the side members of the frame, a pair of knife supports which are mounted upon the said bars and adapted to slide thereon, a double threaded screw mounted at its opposite ends in the side members of the frame, one of the threads on the screw having engagement with a threaded portion of one of the knife supports, and the other threads on the screw having engagement with a threaded portion of the other knife support whereby the knife supports may be simultaneously moved toward and away from each other.

5. A cutting implement comprising a handle portion, a frame adjustably mounted upon said handle portion to vary the angular relationship between the frame and the handle, a pair of cutting knives rigidly secured to said frame and means for adjusting the cutting knives in the frame.

6. A cutting implement comprising a handle portion, a U-shaped member secured to the handle portion, a frame having portions pivotally mounted on the sides of the U-shaped member, a pair of knives rigidly secured in said frame, and means for adjusting the said knives with respect to each other.

7. A cutting implement comprising a frame, a pair of knife supports carried by said frame and adjustable toward and from each other, each of said knife supports having a knife holder comprising a member with a diagonal slot, a knife extending through said slot, and means for holding said knife in adjusted position in the slot.

In testimony whereof, I hereunto affix my signature.

CHARLES HABART.
